UTILITY CART

Russell D. Garlock, Minneapolis, Minn.

Application January 9, 1953, Serial No. 23,086

Term of patent 14 years

(Cl. D14—3)

To all whom it may concern:

Be it known that I, Russell D. Garlock, a citizen of the United States, residing at Minneapolis, county of Hennepin and State of Minnesota, have invented a new, original, and ornamental Design for a Utility Cart, of which the following is a specification, reference being had to the accompanying drawing, forming a part thereof.

Fig. 1 is a perspective view of a utility cart showing my new design; and Fig. 2 is a view in perspective of the structure of Fig. 1 as seen from the bottom.

The dotted line disclosure of a container in

Fig. 1 is shown only for the purpose of illustration.

I claim:

The ornamental design for a utility cart, as shown and described.

RUSSELL D. GARLOCK.
